FOOD WARMING STAND

Michael S. Lax, New York, N. Y., assignor to Kromex
Corporation, Cleveland, Ohio, a corporation of Ohio

Application March 13, 1957, Serial No. 45,240

Term of patent 14 years

(Cl. D81—10)

Fig. 1.

Fig. 2.

Fig. 3.

The dotted line showing in the drawing is for illustration purposes only.

I claim:

The ornamental design for a food warming stand, substantially as shown and described.
